UNITED STATES PATENT OFFICE.

JOSEPH MARION ROSSI, OF NEW YORK, N. Y.

DESIGN FOR A BROOCH OR SIMILAR ARTICLE.

No. 39,034.

Specification for Design.

Patented Jan. 28, 1908.

Application filed August 7, 1907. Serial No. 387,572. Term of patent 14 years.

To all whom it may concern:

Be it known that I, JOSEPH MARION ROSSI, a citizen of the United States, residing at New York, county of New York, State of New York, have invented a new, original, and ornamental Design for a Brooch or Similar Article, of which the following is a specification, reference being had to the accompanying drawing, forming part hereof.

In the drawing Figure 1 is a front view and Fig. 2 a side elevation, disclosing the design.

I claim:

The ornamental design for a brooch or similar article as shown.

JOSEPH MARION ROSSI.
